UNITED STATES PATENT OFFICE.

FREDERIK G. WHITTINGTON, OF EVANSTON, ILLINOIS, ASSIGNOR TO STEWART-WARNER SPEEDOMETER CORPORATION, OF CHICAGO, ILLINOIS, A CORPORATION OF VIRGINIA.

DESIGN FOR AN AUTOMOBILE BUMPER.

Application filed October 1, 1921. Serial No. 504,784. Term of patent 7 years.

To all whom it may concern:

Be it known that I, FREDERIK G. WHITTINGTON, a citizen of the United States, residing at Evanston, in the county of Cook and the State of Illinois, have invented a new, original, and ornamental Design for Automobile Bumper, of which the following is a specification, reference being had to the accompanying drawing, forming a part thereof.

The drawing is a perspective view of an automobile bumper embodying this design and as seen from the front.

I claim:—

The ornamental design for an automobile bumper as shown.

In testimony whereof, I have hereunto set my hand this 27th day of Sept., 1921.

FREDERIK G. WHITTINGTON.
